HEAT EXCHANGER HEADER
CONSTRUCTION

Donald W. Christensen, Racine, Wis., assignor to
Young Radiator Company, a corporation of
Wisconsin

Application September 20, 1944, Serial No. 554,948

1 Claim. (Cl. 257—154)

1

Every type of gas-powered engine requires the use of a heat exchange unit for dissipating the heat from the engine coolant. In automotive equipment it is important to restrict the size and reduce the weight of heat exchange unit, as much as possible, so as to limit and lighten to a minimum the structure of the power unit employed in the transportation of persons and materials. The higher the capacity of such an engine the more expansive must be the heat exchange unit in order to effect the required heat dispersion.

With the Diesel-type engine, the heat dispersion requirements are many-fold greater than with the other types of gas engines. Obviously, this calls for exceptionally expansive heat exchange units. When the Diesel-type engine is employed as the power unit for railroad locomotives heat exchange units of massive heat transfer area are required for the engine coolant in addition to that which may be required for the lubricating oil. Accordingly, there has been presented the problem of providing a heat exchange unit, with adequate heat transfer area, sufficiently compact in form and light in weight to be conveniently arranged within the space available for such engine accessories.

A factor which has had to be considered, and which particularly affects the structure of such units, is the excessive vibration created by high speed travel. Moreover, the roof of a locomotive housing is regarded as the most suitable place for the heat exchange unit. This necessitates providing adequate heat transfer surface within a structure of long and narrow proportions.

It has been found most practical to make up such a heat exchange unit from many separately-assembled heat transfer sections, preferably constructed from light, flat, thin, metal tubes through which the engine coolant passes, and which are finned and exposed to a transverse flow of heat-dispersing cooling medium. Obviously, the assembled sections require a massive header-tank wherewith to deliver and discharge the engine coolant to and from these assembled heat transfer sections. Such header-tanks of necessity have to be quite long and of considerable capacity.

The main objects of this invention, therefore, are to provide an improved form and method of constructing header-tanks for large size, multi-section heat exchange units; to provide an improved form and method of constructing header-tanks especially suitable for use with heat exchange units required for Diesel, or similar high-powered, motor equipment when employed for

2

locomotives where lightness, strength, and compactness, are simultaneous imperatives; to provide an improved form and method of constructing header-tanks of this kind comprising separately shaped, wrought metal forms secured together by the well-known hydrogen-brazing process; and to provide improved header-tanks of this kind which greatly economize the requirements for materials and labor and results in a structure lighter in weight and greater in rigidity than heretofore has been possible with other designs and methods of construction.

In the specific embodiment shown in the drawing:

15 Fig. 1 is a perspective view of a pair of companion heat exchange units designed for use in the roof of a Diesel-powered locomotive, the multiple heat transfer sections of each unit being supported in their assembled relationship by and in communication with header-tanks constructed in accordance with this invention;

20 Fig. 2 is a plan view of one of the heat transfer sections, a multiplicity of which are required to make up one of the companion heat exchange units. A part of the figure is broken away so as to more clearly indicate the internal construction of the finned, flat tubes through which the engine coolant flows;

25 Fig. 3 is an elevation of the structure shown in Fig. 2, various parts of the view likewise being shown in cross-section so as to more clearly illustrate the internal structure of the headers and the finned tubes;

30 Fig. 4 is a fragmentary perspective view of the two separately shaped elements which go to make up the header tank, the parts being shown in spaced relationship prior to their being assembled for the brazing operation;

35 Fig. 5 is a view of these two elements in their assembled relationship immediately prior to the brazing of the elements in a hydrogen-brazing furnace; and

40 Fig. 6 is a fragmentary end view of the brazed header-tank in its completed form, preparatory to attachment to a bank of heat transfer sections.

45 A heat exchange unit, employing header-tanks constructed in accordance with this invention, comprises a plurality of heat transfer sections 1 supported side by side on a pair of the improved header-tanks 8 and 9. The sections 1 are bolted to the header-tanks, by which they are supported, and each section 1 communicates with its supporting header-tank. When used for a Diesel-powered locomotive two of these units, each made

up of eighteen of the sections 7 and a pair of header-tanks 8 and 9, are associated for mounting in the roof of the locomotive, as shown in Fig. 1.

The heat transfer sections 7 are of more or less conventional design. Each comprises a battery 10 of tubes and a pair of headers 11 and 12. The tubes 13 are of the usual flat light metal form, supported at their ends in end plates 14 and 15. Closely spaced fins 16 are mounted on the tubes 13 between the end plates 14 and 15 and are capped on opposite sides by flanged side plates 17 and 18 which form a transverse passage for a cooling medium, usually air, flowing between the fins 16 and around the tubes 13.

The headers 11 and 12 are of identical construction, preferably being in the form of castings. As clearly shown in Figs. 2 and 3, these headers fit within the tube supporting flange plates 14 and 15, thus providing communication between the headers and the engine coolant flowing through the tubes 13. Offsets or extensions 19 are formed on the headers 11 and 12, and their transverse ends 20 are provided with two sets of holes 21 and 22. The holes 21 provide communication with the interior of the headers whereas the holes 22 extend through bosses 23 to receive bolts whereby these sections are secured to the header-tanks 8 and 9, as hereinafter will more clearly appear. As will be noted, the headers 11 and 12 are assembled with the battery 10 of tubes so that the lateral ends 20 are on opposite sides but have their outer faces 24 in parallel planes. These faces are machined so that, upon assembly with the tank headers 8 and 9, a gasket may be used to form a watertight joint between the parts.

The provision of header-tanks, whereby to assemble and support a plurality of these heat exchange sections in a unitary structure with the sections in communicating relationship with the header-tanks, such as shown in Fig. 1, is the primary feature of this invention.

Making the header-tanks 8 and 9 as castings is out of the question. The vibrations to which these header-tanks are subjected in normal use would require a weight for castings that would be prohibitive. Accordingly, it has been necessary to devise a method of forming these header-tanks from two rolled wrought-metal elements subsequently brazing them together. The use of such elements of such length, formed from wrought metal, has presented some difficult problems both as to form and assembly.

Hydrogen brazing is a superior method of uniting two pieces of metal so firmly that the joint is practically as strong as the two pieces of metal themselves. However, the temperature required for such brazing is so high that the form and assembly of wrought metal elements has to be such as to preclude against the possibility of warping or distortion of the elements when subjected to the intense temperatures. For that reason the form of these elements has had to be carefully designed to insure proper resistance to the strains and stresses met with in the welding of two such parts together, as well as strains and stresses to which the header-tanks are subjected in actual use. It is to that end that the two interfitting parts are shaped with the arcuate portions with the particular disposition of the flanges, as will be set forth presently.

The specific embodiment of the header-tank shown in the drawings, employs a pair of rolled, wrought-metal elongated elements 25 and 26.

Each element in transverse cross section is formed with an arcuate portion intermediate extensions and flanges, so that two of the elements may be assembled with the arcuate portions and extensions in opposed spaced relationship with the flanges abutting face to face along which portions the two elements are brazed together whereby the extensions serve to appropriately space the arcuate sections apart so as to provide an open-ended conduit extending the length of the assembled elements.

In the forming of element 25, the arcuate portion 27 is of nearly semi-circular form and has a tangential extension 28 formed along one edge 15 of the arcuate portion and an angularly disposed extension 29, formed along the other edge. These extensions terminate in flanges 30 and 31, respectively. The extension 29 is positioned at exactly a 90° angle to the flange 30. Between extension 29 and the flange 31 there is an angular offset 32 which serves to space the flange 31 inwardly from the extension 29 and thus provides for a spacing apart of the extension 29 from the corresponding extension on the other element. 20 A series of holes 33 are formed in the extension 29 throughout the length of the element.

The element 26 likewise has an arcuate section 34, but of materially less circumferential length than the arcuate section 27 of the element 25. A 30 flange 35 is formed along one longitudinal edge of the arcuate section 34; along the other edge is formed on extension 36 disposed at right angles to the flanges 35 and terminating in flange 37. Holes 38 are likewise formed throughout the 35 length of the extension 36, positioned so as to register with the holes 33 when the parts are assembled. In this case, however, the holes 38 are counter-bored from the inside so as to form a shoulder 39 in connection with each of the 40 holes 38. Flanges 31 and 37 are slightly offset from the planes of the extensions 29 and 36. This is made necessary so as to space the flanges slightly away from the adjacent edges 40 of the headers 11 and 12 when they are attached to the 45 tank headers 8 and 9. Also the flange 30 is slightly offset from alignment with the extension 28.

The two elements, 25 and 26, are assembled with the flanges 30 and 35 and the flanges 31 and 37 abutting face to face (as shown in Figs. 5 and 6) with the arcuate sections 27 and 34 and the extensions 29 and 36 opposed and spaced apart so as to form an open-end conduit extending throughout the length of the assembled elements.

With the two elements thus assembled and placed in the position shown in Fig. 5, sleeves or bushings 41 are press-fitted into the holes 33 and 38 and set against the shoulders 39, with the inner diameter of the sleeves 41 in registration with the holes 38 in the extension 36.

With the two elements 25 and 26 temporarily clamped in their assembled positions by any 65 suitable means, and the bushings 41 pressed into place, the header-tank is ready for brazing. Prior to the brazing operation rods of copper 42 and 43 (see Fig. 5) are placed inside the assembled elements along the junctures of the flanges 30 and 35, and 31 and 37, respectively. Likewise, 70 rings of copper 44 and 45 are placed around the bushings 41, directly above their juncture with the respective extensions 29 and 36. Such placing of copper rods and rings is a feature in the 75 well-known hydrogen-brazing process whereby

two metals subjected to an intensive heat are firmly welded, or brazed, together.

In a hydrogen-brazing furnace for this purpose, the temperature approximates 2050° F. Obviously this brings the metal to an almost white heat and the copper rods and rings melt and run in between the contiguous joints, forming a film throughout the length of the joint which binds the contacting metals so firmly together that it would require as much force to break the joint as would be required to sever the metal itself. The nature of this film is suggested by the lines 46 and the shading 47, in Fig. 6.

Because of this intensive heat the cross-sectional contour of the elements—the relative arrangement of the arcuate portions and the angular positioning of the extensions and flanges—has had to be designed so that there will be no sagging or collapsing of any portion of the elements during the brazing operation. Accordingly, the cross-sectional design has then developed so as to resist the contemplated forces tending to warp or distort these elements when subjected to the brazing furnace temperature with the parts assembled as shown in Fig. 5.

With the parts thus assembled, a header-tank is placed in the hydrogen-brazing furnace. Being of such a great length, and it being imperative to heat the entire header-tank to the desired temperature uniformly throughout its length in order to avoid any possibility of warping, it is necessary to have a hydrogen-brazing furnace of a size sufficient to accommodate the full length of one of these header-tanks. For the same reason it is necessary to have a cooling chamber of a length sufficient to accommodate one of these header-tanks allowing it to cool uniformly throughout its length to avoid the possibility of warping.

After the header unit has become cooled, following the brazing process, holes 48 are drilled in the extension 29 in between the holes 33. The holes 46 are positioned to register with the holes 21 in the headers 11 and 12 for the heat transfer sections 7.

One end of each header tank has a cap 49 welded thereto so as to completely close one end, and the other end has a fitting 50 welded thereto so as to provide for a connection with the source of supply of the engine coolant.

A header-tank so constructed is ready for assembly with a plurality of heat transfer sections 7, to constitute a complete heat exchange unit as shown in Fig. 1. As will be more or less evident from this view, the header-tanks 8 are arranged along the inner edges of the assembled heat transfer sections 7, whereas the header-tanks 9 are attached along the outer edges. In each case the attachment is made by using bolts, or

rivets 51, preferably the former, extending through the registering holes 22, of the heat transfer section headers 11 and 12, and the bushings 41 of the header-tanks 8 and 9. Obviously, a gasket would be inserted between the extension 36 and the abutting headers of the heat transfer sections 7 so as to form fluid-tight joints around the registering holes 21 and 48 of the heat transfer section headers 11 and 12, and the header-tanks 8 and 9, respectively.

Variations and modifications in the details of the structure and arrangements of the parts of this invention may be resorted to without departing from the spirit and coverage of the appended claim.

I claim:

An article of manufacture of the class described comprising, a pair of separately-rolled wrought-metal elements each of a straight length many times its width, one of said elements in transverse cross-section being formed with an arcuate-shaped portion intermediate lateral flanged extensions, one of which extensions is disposed approximately tangentially with respect to said arcuate-shaped portion and the other of which extensions is L-shaped with the two parts thereof respectively disposed transversely to and in the same general direction as said one extension, the other said element in transverse cross-section being formed with an arcuate-shaped portion intermediate a lateral flange and a lateral flanged extension, said elements being assembled with the faces of said flanges abutting and the extension on said other element directly opposed to said L-shaped extension on said one element whereby said arcuate-shaped portions are supported in opposed spaced relationship to form a conduit the length of said elements, said elements being hydrogen-brazed along said abutting flange faces, end closures for said assembled elements, and a series of bushings interposed between registering apertures in and hydrogen-brazed to said above-mentioned opposed extensions, one of said elements having ports communicating with said conduit.
